AMPLIFIER

Hiroaki Yazawa, Yamatokoriyama, and Yoshiaki Iida,
Neyagawa, Japan, assignors to Matsushita Electric In-
dustrial Co., Ltd., Oaza-Kadoma, Kadoma-shi, Osaka,
Japan

Filed Apr. 6, 1971, Ser. No. 131,840

Term of patent 14 years

Int. Cl. D14—03

U.S. Cl. D26—14

FIG. 1

FIG. 2

FIG. 1 is a front, top and right side perspective view of an amplifier, showing our new design;

FIG. 2 is a left side, bottom and rear perspective view.

Portions of the drawing figures are shaded to indicate contrast in appearance, and a portion of FIG. 1 has been diagonally lined to indicate transparency.

We claim:

The ornamental design for an amplifier, as shown and described.
